UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,071, dated September 9, 1902.

Application filed July 29, 1902. Serial No. 117,590. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is shown in front elevation.

The leading features of my design consist in a frame each of the sides of which is ornamented with a column having somewhat the resemblance of a candelabrum and surmounted by the figure of a child. The cross-piece, which is in the shape of a hood, has a casket or shield-like device at its center, with scrollwork ornamentation below the same and extending from each side thereof. The

summer front below the top piece has a diamond-shaped formation, each of the diamonds inclosing or containing a flower. At the center of the summer front is an outwardly-extending ribbed open scrollwork portion. Below the summer front is an open-work frame, the top portion of which shows a row of censers and the bottom portion of which is ornamented with variously-disposed scrolls and diagonal lines forming diamonds extending from a central dome-like figure.

I claim—

The ornamental design for a fireplace-front as shown and described.

In witness whereof I have hereunto set my hand.

THOMAS M. DUDGEON.
